United States Patent Office

Des. 232,152
Patented July 23, 1974

232,152

COMBINED CONTAINER AND CLOSURE THEREFOR

William H. Roper, Los Angeles, Robert E. Roper, Los Alamitos, and Charles R. Roper, Huntington Beach, Calif., assignors to Frank Roper, North Hollywood, and Ralph A. Miller, Van Nuys, Calif., fractional part interest to each

Filed May 17, 1972, Ser. No. 254,348

Term of patent 14 years

Int. Cl. D7—07

U.S. Cl. D7—187

Fig. 1.

3

Fig. 2.

3

Fig. 3.

Fig. 4.

FIG. 1 is top plan view of a combined container and closure therefor showing our new design;

FIG. 2 is a left-side elevational view;

FIG. 3 is a corner elevational view taken in the direction of arrows 3—3 in FIG. 1; and

FIG. 4 is a bottom plan view.

We claim:

The ornamental design for a combined container and closure therefor, as shown.
